[57] **CLAIM**

The ornamental design for a saw blade with vents, as shown and described.

DESCRIPTION

FIG. 1 is a top plan view of one embodiment of the saw blade with vents of the present invention, the bottom plan view being a mirror image of FIG. 1;

FIG. 2 is a left-side elevational view of the saw blade with vents of FIG. 1;

FIG. 3 is a right-side elevational view of the saw blade with vents of FIG. 1;

FIG. 4 is a top side elevational view of the saw blade with vents of FIG. 1;

FIG. 5 is a bottom side elevational view of the saw blade with vents of FIG. 1; and,

FIG. 6 is a top plan view of a second embodiment of the saw blade with vents of the present invention, the bottom plan view being a mirror image of FIG. 6, and all four side elevational views thereof being the same as FIGS. 2 through 5, respectively.
